UNITED STATES PATENT OFFICE

2,440,446

APPARATUS FOR COOLING OR CONDITION-
ING AIR OR OTHER FLUIDS

Richard Joseph Kenny, Bhowra, British India

Application July 12, 1945, Serial No. 604,708
In British India July 31, 1944

3 Claims. (Cl. 261—92)

1

This invention relates to a machine for cooling fluids and for cooling and humidifying in very dry climates, conditioning and to a lesser extent for cleaning air by washing, the cooling and humidifying being effected by means of evaporation of water in a dry climate, and the washing is being effected by causing the air to be conditioned to come into intimate contact with films of water which will have the effect not only of cooling by evaporation but will also pick up and remove dust and impurities from the air.

The invention is also applicable to cooling water by evaporation of part of the water by the passage in contact therewith of a draught of air.

An object of the invention is to effect these results at a low capital expenditure and running costs.

The apparatus is of the kind comprising a casing, a rotary drum within the casing, consisting of any desired number of perforated circumferential layers, forming an evaporating surface, a water tank below the drum for wetting the lower parts of the said layers as the drum rotates, a fan facing one end of the drum for supplying a draught of air through the drum, and vanes or the like secured to the inside of the drum to rotate it when the draught of air from the fan passes therethrough.

In apparatus of this kind there is a tendency for the air discharged from the fan to take the easiest path, viz. leak through between the open end of the drum and the casing. Its failing to go through the drum has two effects: (1) the driving power of the vanes secured to the inside of the drum is reduced and therewith also the power of lifting the water picked up by the lower side of the drum, and (2) the amount of air passing through the films of water spread over the perforated layers is also reduced.

According to the present invention these reductions are prevented or checked by the provision of an air leakage check ring secured to the end of the drum facing the fan and provided with blades so inclined to the axis of the drum that the air passing into the check ring will cause these blades to rotate the drum in the same direction as it is turned by the vanes secured to the inside of the drum. A cowl is also preferably provided to prevent the air discharged by the fan from passing direct into the casing and to compel it to pass through the bladed check ring and in between the perforated layers of the drum, for which purpose the cowl, which is fixed to the end of the casing, surrounds the open end of the drum.

In order to extend the flow of the air through

the layers of the drum, and thereby increase the evaporating effect, each layer, preferably made of expanded metal, is helically wound round with a mat surface like material, leaving narrow spaces between the various convolutions, and the spaces between the convolutions of each layer are staggered relatively to the spaces of the convolutions of the layer above or below it, so that the air is caused to pass in a zig-zag or devious path as it escapes from the interior of the drum.

In this apparatus, although the main elements for causing the drum to rotate are vanes or the equivalent on the drum adapted to cause rotation of the drum when the fan supplying air to the apparatus is started, a starting mechanism for mechanically rotating the drum may be provided, adapted to be effective particularly when the working of the apparatus is just starting. For this purpose the fan for supplying air to the apparatus may drive a second shaft by means of a belt at a much reduced number of revolutions per minute than the R.P.M. of the fan, and said second shaft in turn drive the drum by means of a belt—at a very slow speed of revolution.

Means may be provided whereby the level in the water tank, receptacle or bath may be regulated to a desired level.

The invention will now be described with reference to the accompanying drawings, in which:

Fig. 1 shows, mainly in cross-section, a form which the apparatus may take. This is partly shown diagrammatically.

Fig. 2 is a cross-section of Figure 1, for example on lines A—B of Figure 1.

Fig. 3 is a view of the rotor member in the form of a drum or cylinder showing how one form of it may be wound.

Fig. 4 is a fragmental cross section of a part of the drum shown to a larger scale, and

Fig. 5 is a diagram showing an auxiliary drive to be used particularly when starting the apparatus.

Turning now to Figures 1 and 2, the drum or cylinder 1 of the rotor member is mounted on a shaft 2 which is mounted in bearings 3 and 4 which will be some type of anti-friction bearing, such as ball bearings or roller bearings, or at least should be bearings which give very little resistance to rotation of the drum. From the shaft three spiders or wheels, 5, 6 and 7, support the evaporation surface of the drum. These wheels or spiders have rims 8, 8 upon which the drum surface may be built up. A convenient form of drum surface is one wherein a layer of expanded metal 9 is curved to cylindrical shape and is attached

to the said rims 8, 8. Around this layer of expanded metal tape or webbing 10, as most clearly shown in Figures 3 and 4, is wound, said tape or webbing being wound round in a helix with narrow spaces 11, 11 between the various convolutions of the tape or webbing. On the outside of the first layer 9 of the expanded metal spacers 12, 12 formed, for example, of small diameter iron rod, are placed. As there are three wheels or spiders, 5, 6 and 7, such a spacer 12 will be placed opposite each of these. Another layer 9a of expanded metal is then placed supported by the rings 12 and spaced away from the first layer 9. Around this again tape or webbing 10a is wound in the same way as the first layer. The space between the convolutions of this second layer 10a would be in staggered relationship to the spaces between the windings or convolutions of the tape in the first layer 10. Having built up two layers further rods or spacers 12a are placed in position, surrounding and outside the first set of rods or spacers 12, and a third layer 9b of expanded metal is placed therearound, which will thus be spaced away from the second layer 9a. This third layer of expanded metal 9b is also wrapped with tape or webbing, as shown at 10b. Finally, another spacing member, 12b may be placed in position to support the outermost layer 9c of the expanded metal or the like. Round this layer 9c of expanded metal, the fourth layer of tape or webbing is wound as a helix thereby giving the drum four layers of tape or webbing through which the air is caused to pass in a zig-zag or devious path as it escapes from the interior of the drum.

The drum 1 is supported above a water receptacle, tank or trough 13 which is kept full of water in order that it shall keep the drum suitably moistened as the drum is caused to rotate.

In order to supply air to be conditioned and also to cause the drum to rotate, the fan 14 is provided, the fan blades being shown at 15. The fan motor has a shaft 16 which, however, is completely separate from the shaft 2 of the drum. The fan may be supported in any desired manner, for example by the framing 17.

Inside the drum 1 a series of rotation causing elements in the form of blades or vanes are fixed to the wheels or spiders 5 and 6. For example, to the wheel or spider 5 eight vanes, such as 18, may be fixed, these blades being fixed at such an angle and, if desired, being given such a twist that as the draught of air from the fan 14 is forced into and flows longitudinally into the drum 1, the drum will be caused to rotate.

On the second wheel or spider 6 of the drum further blades or vanes, 19, 19 may be fixed. These conveniently may be half as many in number as are required for the first set of blades or vanes 18.

The end of the drum or cylinder 1 opposite to the open end through which the fan delivers its draught of air will be closed, for example with cloth or plywood 20, so that the air which is forced by the fan blades 15 into the cylinder or drum 1 will be forced to pass out of the drum through the water soaked layers of webbing or the like 10 to 10c which have already been described.

It will thus be seen that under the action of the fan blades 15, the air not only is caused to flow into the drum 1 and to pass out through the cylindrical walls of the drum; but also the drum is caused to rotate. The lower side of the drum dips into the water bath 13 which is kept full of water to about the level 21, and hence—owing to the action of the draught on the blades—the drum

is continuously kept wet owing to its being rotated by the draught acting upon the blades or vanes 18 and 19 respectively. The air thus passes by a devious path through the walls of the rotating drum where it comes into contact with, or passes through, or flows over films of water. The air is thus cooled by evaporation of water. The drum as mounted is inside a casing 22 which is fixed to a door or window opening 23. In this door or window opening louvres such as 24, 24 may be fixed through which the conditioned air enters the house or building.

As there is some tendency for the air discharged from the fan to take the easiest path, it may be that part of the air discharged by the fan blades 15 will fail to go through the layers of webbing or fabric 10—10c and instead will leak through between the open end of the drum and the end 25 of the casing. In order to prevent this, or at least to check this, a cowl 26 is fitted to the end 25 of the casing and projects inwards overlapping the open end of the drum. The open end of the drum is itself surrounded by an air leakage check ring 27. This air leakage check ring is mounted upon the outside of the drum 1 at the open end of the drum upon a series of devices or blades, shown diagrammatically on the drawing at 28, 28, which are inclined to the axis of the drum, so that air passing into this air leakage check ring through the annular space between it and the drum will cause, by these blades, the drum to rotate in the same direction as the rotation caused by the main blades 18 and 19. That is to say that air passing between these blades 28 will add its quota to the rotation of the drum. In order that this air leakage check ring may be properly supported, the drum, as carried by the wheel or spider 5, may be somewhat more solidly built up at its open end. The air leakage check ring 27 may furthermore be helically wound with tape or webbing which will be kept moistened with water, as this ring also passes through the water bath, and thus the air passing through the annular space between the ring 27 and the drum 1 will be cooled.

It is important that the bath 13 shall be kept full of water because for an eight roomed bungalow in the really hot weather there is an evaporation of about 2 gallons of water per hour. This bath may be hand-filled as through the funnel 29 (see Fig. 2). Alternatively, if so desired, a ball float valve 30 may be provided, so that the water coming through the water pipe 31 will keep the level of the water in the bath at a desired level 21. A suitable drain cock for the water 32 is shown so that the tank 13 may be emptied when desired.

If the apparatus is left standing for a considerable time, the water in the upper part of the drum surface above the level of the water in the tank 13 evaporates and the drum becomes dry, except for the small portion dipping below the surface of the water in the tank 13. Under such conditions the drum is in unstable equilibrium because the wet part of the drum is the heavier and it is thus more difficult to cause the drum to start rotating, and, under certain conditions, it may be that the drum might not rotate upon the starting of the fan 14. It is therefore desirable to have an alternative method whereby the drum may be caused to rotate until it is completely wet all round and thus equally balanced. A convenient alternative arrangement is shown in Figure 5 which is merely a diagram. According to this figure it will be seen that there is a gap 33 between the shaft 2 of the drum 1 and the shaft

16 of the fan 14, so that there is no direct drive to the drum. On the shaft 16 of the fan a small diameter pulley 34 is mounted, which drives a counter-shaft 35 to which a large wheel, for example a bicycle wheel, 36, is fixed, the drive being by means of the belt 37. This counter-shaft 35 is supported in bearings 38, 39 and has a further small pulley wheel 39 fixed thereto, which, through the belt 40 which passes round the drum 1, will cause the drum 1 to rotate very slowly when the fan 14 is switched on.

As this subsidiary mechanism is only required at the starting stage to overcome the resistance to motion when the drum is in unbalanced equilibrium, when not needed for this purpose it may be arranged to idle. Alternatively a clutch arrangement 41 mounted between the bearings 42, 42 on the shaft 35 may be provided. Alternatively, some other method of starting the rotation of the drum, when the upper part of the drum is dry, may be provided.

It is to be quite understood, however, that these subsidiary methods of driving are merely subsidiary to the main method whereby the rotation of the drum is mainly due to the action of the draught from the fan.

According to an experimental form of the machine, the rotor as designed for an eight-roomed bungalow, is about 3 ft. in diameter by about 3' long (but these dimensions can be varied according to the size of the machine required). This rotor revolves on two sets of ball bearings being carried by a light shaft. There are three wheels mounted inside the drum on the shaft to carry the drum. The drum consists of an inner layer of expanded metal over which are wound strips of cloth or tape, preferably about 2" wide, the windings being so applied that an air space of about $\frac{1}{4}$ " in width is left between each winding or convolution of the tape and the next. Over this first part of the drum surface, three spacing rings—each $\frac{1}{4}$ " in diameter or in thickness—are placed, and another layer of expanded metal also covered with 2" tape winding is built up, the convolutions of this tape being in staggered relationship to the convolutions in the first layer. Altogether in this way, four layers of tape are built up.

The blades or vanes forming the elements for rotating the rotor or drum are fitted to the spokes of two of the wheels or spiders carrying the drum; but in the case of the third wheel or spider, the end of the drum is merely blanked off or closed up by using a disc of ordinary cloth or plywood.

The position and angle of the blades such as 18 and 19 helps to break up the air stream and disperses the air stream in the required direction towards the inner sides of the drum instead of allowing the full force of the air stream to impinge upon the closed end of the drum.

With a machine of the size suggested, a fan having 24" blades has been found very convenient.

It will of course be understood that the invention is not restricted to the details described and illustrated. For example, although it has been found very advantageous to use tape or webbing which is continuously passing through the water in the water tank, this is not absolutely essential. The tape, however, being soaked with water, carries a film of water with it and the air passing through in a devious or zig-zag path in contact with thin films of water evaporates the water rapidly and cools very rapidly. The drum

usually rotates at about one revolution per minute or perhaps moves somewhat slower.

In place of the tape or webbing it would be quite satisfactory to use a porous cloth or fabric, or even Khus-khus or the like, or any material which will soak up water and will allow the passage of air therethrough.

The subsidiary rotation means which have been described are not intended to be a means of driving the drum continuously. The intention is that the said means, once the drum is being driven by the draught of air from the fan, will either be switched off or will merely idle. The subsidiary means will generally be so geared that when the fan is turned on it will only be able to drive the drum at a speed somewhat less than the speed at which the drum will normally be driven by the fan. Alternatively, hand-operated means might be applied. For example to the further end of the drum gearing may be applied, so that upon, or prior to, switching on the fan 14, the drum may be rotated by such hand-operated gearing the parts or belts of which would not necessarily enter the water tank at all, and this gearing might be fitted with a free wheel arrangement so that it will simply idle when once the apparatus is operating under normal conditions.

The direction of the draught might be reversed and the fan used to draw air into the drum and out again to rotate the drum.

30 A casing and louvres are not absolutely essential.

The water for cooling the air also effects a certain washing of the air by removing dust and impurities from the air which dust or the like find their way into the receptacle for water below the drum.

The apparatus is not only adapted for the cooling of air which is caused to pass therethrough but can be used for the cooling of other fluids; for example it may be adapted to cool water—the draught of air passing through the apparatus causing the water used for wetting the rotating member (or rotor) to be partially evaporated, and, in the process of evaporation the rest of the water flowing down is cooled.

When the intention is to use the apparatus particularly for cooling water extra water, if so desired, above that amount which is raised by the 50 slow rotation of the rotating member (or rotor) may be supplied to the top of the said member, for example by a perforated pipe from an overhead source of supply, and this water be cooled by many degrees before reaching the tank beneath by the evaporation of a relatively small proportion of the water.

I claim:

1. An apparatus for cooling or conditioning air or other fluid, comprising in combination a casing, a rotary drum within the casing, consisting of at least one perforated circumferential layer, forming an evaporating surface, a water tank below the drum for wetting the lower part of the said layer as the drum rotates, a fan facing one 60 end of the drum for supplying a draught of air through the drum, vanes secured to the inside of the drum to rotate it when the draught of air from the fan passes therethrough, an air leakage check ring secured to the end of the drum facing the fan and blades provided on the said check ring which are so inclined to the axis of the drum that the air passing into the check ring will cause these blades to rotate the drum in the same direction as it is turned by the vanes secured to the inside of the drum.

2. An apparatus for cooling or conditioning air or other fluid as claimed in claim 1, and in which the drum consists of a plurality of perforated circumferential layers one within the other, forming an evaporating surface, each perforated layer being helically wound round with a material leaving narrow spaces between the various convolutions, the spaces between the convolutions of each layer being staggered relatively to the spaces of the convolutions of the layer above or below it, whereby the air is caused to pass in a zig-zag path as it escapes from the interior of the drum.

3. An apparatus for cooling or conditioning air or other fluid as claimed in claim 1, and in which the drum consists of a plurality of perforated circumferential layers one within the other, forming an evaporating surface, each perforated layer being helically wound round with a tape leaving narrow spaces between the various convolutions, the spaces between the convolutions of each layer being staggered relatively to the spaces of the

10

5

casing at a point between the fan and the open end of the drum and surrounding the latter open end, whereby the air discharged by the fan is compelled to pass through the bladed check ring and in between the perforated layers of the drum.

10 RICHARD JOSEPH KENNY.
